UNITED STATES PATENT OFFICE.

ARTHUR SHORROCK, OF NORTH ADAMS, MASSACHUSETTS.

CANDLE-GUARD.

1,211,251.

Specification of Letters Patent. Patented Jan. 2, 1917.

Application filed February 23, 1916. Serial No. 79,921.

To all whom it may concern:

Be it known that I, ARTHUR SHORROCK, a citizen of the United States, and a resident of North Adams, in the county of 5 Berkshire and State of Massachusetts, have invented a new and Improved Candle-Guard, of which the following is a full, clear, and exact description.

The object of the invention is to provide 10 a new and improved candle guard arranged to shield surrounding parts against being accidentally set on fire, scorched, carbonized or otherwise injured.

In order to accomplish the desired result 15 use is made of a skeleton frame having at its base a support for the candle and a tubular guard of wire netting extending within the said frame and attached to the base and top thereof to centrally inclose the candle.

20 A practical embodiment of the invention is represented in the accompanying drawings forming a part of this specification, in which similar characters of reference indicate corresponding parts in all the views.

25 Figure 1 is a side elevation of the candle guard with a candle in position therein; Fig. 2 is a sectional side elevation of the same; Fig. 3 is a similar view of a lower portion of the same and showing the extinguisher for the candle in action; Fig. 4 is a 30 cross section of the lower portion of the candle guard, the section being on the line 4—4 of Fig. 1; and Fig. 5 is a sectional plan view of the same on the line 5—5 of Fig. 1.

35 The candle 10 extends centrally within a tubular guard 11 of wire netting surrounded by a skeleton frame 12 formed of a number of wires 13 bent inwardly at their upper 40 portions and terminating in eyes 14 through which passes a wire ring 15 to which the apex of the upper conical end of the guard 11 is attached. A hanger 16 is connected with the upper end of the skeleton frame 12 for suspending the device and with it the candle 10 from a suitable support.

45 The lower ends of the wires 13 are bent inwardly to form radial bars 17 to which the lower or base end of the guard 11 is attached by wire loops 18 depending from the base of the said guard 11. The wires 13 are formed into eyes 19 a short distance above the radial members 17 and through the eyes 19 extends a wire ring 20 to reinforce the 50 lower portion of the skeleton frame 12. The inner ends of the members 17 terminate in

open eyes or spring hooks 21 for removable engagement by a wire ring 22 forming a part of the candle holder and which latter is arranged as follows: A supporting plate 25 50 extends diametrically within the ring 22 and terminates in upwardly extending prongs 26 bearing against the exterior of the candle 10 at diametrically opposite points, and the said prongs 26 are provided near their 55 lower ends with eyes 27 through which extends the ring 22 thus supporting the candle holder. Another pair of prongs 28 alternates with the prongs 26 and has its upper terminals 29 bearing against the exterior of 60 the candle 10 at diametrically opposite points. The prongs 28 are pivoted on the ring 22 and are provided with depending arms 30 pressed apart by a spring 31 connected at its ends to the arms 30. The arms 65 70 are taken hold of by the user between the thumb and forefinger to open the prongs 28 for the insertion of the candle 10, and after this has been done and the candle rests on the supporting plate 25 then the operator 75 releases the arms 30 to allow the spring 31 to press the arms 30 apart thus causing the terminals 29 to bear firmly against the exterior of the candle 10. When the candle 10 has burned down below the terminals 29 80 85 then the prongs 28 gradually close by the action of the spring 31 so that the terminals 29 engage the burning wick and clamp the same between the terminals to extinguish the flames. 90

It will be noticed that by having the wire netting guard 11 spaced from the candle 10 the flame thereof is prevented from setting surrounding parts on fire or injuring the same, and in addition the guard wire 13 of 95 the skeleton frame 12 keep the curtains or other loose surrounding parts from being blown against the guard 11 thus avoiding injury to the same.

The candle holder guard and extinguisher 100 shown and described can be readily used for candles intended for illuminating Christmas trees or for use in Japanese paper lanterns or in pasteboard boxes such as are used by photographers in a dark room, and it is 105 evident that I do not limit myself to any particular use of the device.

Having thus described my invention, I claim as new and desire to secure by Letters Patent:

1. A candle guard, comprising a skeleton frame and a mantle of wire netting arranged

- within the said frame and spaced therefrom at the sides, the upper and lower ends of the mantle being attached to the upper and lower ends of the skeleton frame.
2. A candle guard, comprising a skeleton frame made of wire and having a base, the upper ends of the wire being bent inward and connected with each other at their upper terminals, and a tubular mantle of wire netting arranged within the said skeleton frame and having its upper end conical and connected with the upper end of the skeleton frame, the lower end of the mantle being attached to the said base.
3. A candle guard, comprising a skeleton frame made of wire and having a base, the upper ends of the wire being bent inward and connected with each other at their upper terminals, a tubular mantle of wire netting arranged within the said skeleton frame and having its upper end conical and connected with the upper end of the skeleton frame, the lower end of the mantle being attached to the said base, and a support for the candle attached to the said base and arranged centrally relatively to the said mantle.
4. A candle guard, comprising a skeleton frame made of wire and having a base, the upper ends of the wire being bent inward and connected with each other at their upper terminals, a tubular mantle of wire netting arranged within the said skeleton frame and having its upper end conical and connected with the upper end of the skeleton frame, the lower end of the mantle being attached to the said base, and a support for the candle attached to the said base and arranged centrally relatively to the said mantle.
5. A candle holder having a supporting member and provided with a pair of oppositely disposed fixed prongs adapted to bear against the exterior surface of the candle, and a pair of oppositely disposed pivoted prongs alternating with the said fixed prongs and likewise adapted to bear against the surface of the candle, the said pivoted prongs having arms extending beyond the pivots, and a spring connected with the arms to press the same apart and cause the pivoted prongs to move toward each other.
6. A candle guard, comprising a tubular foraminated metal mantle, and a candle holder in the lower end of the mantle, said holder having a pair of oppositely disposed fixed prongs and a pair of pivoted and spring pressed prongs at right angles to the fixed prongs, said pivoted prongs having members extending below the lower end of the mantle.

In testimony whereof I have signed my name to this specification in the presence of two subscribing witnesses.

ARTHUR SHORROCK.
